UNITED STATES PATENT OFFICE.

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY.

GAS RANGE AND BURNER THEREFOR.

Application filed November 5, 1923. Serial No. 672,920.

To all whom it may concern:

Be it known that I, ARTHUR STOCKSTROM, a citizen of the United States, residing at St. Louis and State of Missouri, have invented certain new and useful Improvements in Gas Ranges and Burners Therefor, of which the following is a specification, reference being had therein to the accompanying drawing.

10 This invention relates to improvements in gas ranges and burners therefor and it pertains to certain improved constructions and arrangements which will be hereinafter described.

15 The primary object of the present invention is the supporting of a combined blue flame radiant heat burner midway an unincumbered housing, whereby the lower part of the housing constitutes a broiling oven, 20 and the upper portion of the housing a baking oven.

A further object of the present invention is providing combined horizontally arranged radiants with blue flame burners beneath it, and to support a baffle immediately above the radiant burners, the said baffle only partially extending across the housing, whereby the heat from the radiants is radiated and flows around the edges of the 25 baffle and rapidly heats the baking oven, and at the same time provides a broiling oven beneath the burner.

30 A further object of the present invention is to provide a burner with horizontally arranged radiants which is constructed as a separate fixture to be readily lifted from its support and from its blue flame burner beneath whereby it is capable of repair without in any manner disturbing the blue 35 flame burner.

Another object of my invention is to provide a burner comprising horizontally arranged radiants, and a baffle plate connected with the radiant supports whereby the 40 radiants and baffle are separate and independent members resting upon and are removable together, for the purpose of repair, or for any other reason.

45 A further object of the present invention is to provide a gas range with a vertical elongated housing unincumbered within the housing, and providing the unincumbered housing with a horizontally arranged radiant burner carrying a baffle, whereby the

construction of the oven is much simplified and cheapened.

50 Another object of my present invention is to arrange parallel blue flame burners approximately midway a vertically elongated housing, and provide horizontal radiants 60 extending inward from the blue flame burners, the said radiants carrying a baffle above them, the said radiants and baffle resting upon and freely removable from the blue flame burners, for the purpose described.

55 Other objects of the present invention will appear from the following description.

60 In the accompanying drawings Fig. 1 is a vertical sectional view through a part of the housing, the section being transverse to the said radiant, the blue flame burner, and baffle plate thereabove.

65 Fig. 2 is a section view through the housing on the dotted line 2—2 of Fig. 1 looking in the direction indicated by arrow.

70 Fig. 3 is a detached perspective view of the removable radiants and baffle plate, the blue flame burner being shown in dotted lines.

75 Referring to the drawings in which, 1 indicates a vertically elongated housing having supported in the baking oven 3 a plurality of grate supporting members 2, and a plurality of grate supporting members 4 in the broiling oven 5.

80 My improved burner A is supported within the oven substantially or approximately at its center.

85 From the foregoing description it will be observed that the housing 1 has its interior wholly unobstructed, except by the burner and its cooperating parts, which will be presently referred to. This arrangement cheapens the construction of the oven and makes it relatively simple and cheap to construct.

90 My improved burner A comprises a manifold which consists of an inlet arm 7, the said arm being attached to the oven 1 at the point 8. The inner end 9 of the manifold arm is connected with a manifold 10, the opposite ends of this manifold being connected with the blue flame burners 11. 100 The connecting portion 10 of the manifold is wholly closed whereas the burners 11 have outlets 12 at their inner sides. The manifold in addition to having the ends of its 105

arm 7 attached at the point 8 is also attached to a transverse member 12' at the back of the housing and a transverse member 13 at the front of the housing, the member 12' being bolted to the wall of the housing as at 14 and the member 13 bolted to the housing as at 15. Therefore the manifold remains in the oven.

Immediately above the burners 11 are supported the inwardly extending radiants 16, the outer ends of the radiants resting in a U-shaped rail 17 and their inner ends in a U-shaped or slotted rail 18. Attached to these rails are vertically extending baffle supports 19 which have a baffle 20 attached to the supports both at its ends and at its center by suitable bolts 21. Arms 22 formed as a part of, or attached to the arms 19, have their lower ends constructed to fit on the burners 11, whereby the burner 6 with its cooperating constructions simply rests freely upon the burners 11, and may be lifted from the burners as occasion may make it necessary. This burner and its co-operating parts are free from attachment to any other part of the burner construction making it freely removable for the purpose of repairing or replacing the radiants or for any other purpose.

Preferably I utilize a thermostatic housing 23 carrying a thermostatic lever 24 having its lower end 25 controlling the flow of gas from the housing into the outer end of the arm 7 of the manifold. The upper end 35 of the lever is operatively connected with the outer end of a thermostatic element 25 which extends into the oven. By means of a regulating wheel 26 the thermostatic arrangement can be regulated for controlling the flow of gas for any desired regulated amount of heat in the oven. The said thermostat and its construction involves the invention described in Meacham Patent No. 1,236,335, August 7, 1917, which describes 40 its operation. Briefly speaking the wheel 26 is set to the degree of heat desired in the oven for cooking any article. When the heat has reached that point then the thermostat closes off the gas and maintains the oven at that heat until the article is cooked.

By a series of tests I find that in the use of this burner there is considerable less gas used to maintain a predetermined heat than is necessary with the usual blue flame burner alone.

I have found that in the operation of the burner there is an absolutely perfect combustion. All of the gas passing through the burners 12 is absolutely consumed as it flows over the incandescent radiants. This is not the case with the ordinary blue flame burner and hence is a saving in gas to that extent. In addition the radiants cause a high rate of heat transmission as well as an equal distribution of the heat in the

housing. The baffle is for the purpose of preventing the heat from immediately rising above the radiants to its full extent making it liable to burn any article above. By means of this baffle plate the majority of 70 the heat is caused to flow out through the spaces 27 at the sides and ends of the radiant burner and quickly establishes the desired adjusted heat in the housing.

Attention is called to the fact that the 75 baffle 20 is not a division plate of this housing as there is considerable space all around the baffle, the baffle acting only as a baffle pure and simple. The housing is therefore uninterrupted both above and below the 80 burner and its cooperating parts.

For the purpose of convenience in lighting the burners 12 I provide a pilot tube 28 which extends from a thermostatic housing 23 within the range housing 1 and this 85 tube 28 has a burner 29 for one of the burners 11, and then extends across to the opposite side and furnishes a pilot 30 for the burner 11 at the opposite side. When starting the burner the valve 31 is opened and a match touched to each of the pilots 29 and 30 which ignites the burners 11.

Air is combined with the gas from the valve 23' so that combined air and gas in proper proportions is supplied to the burners 11, and this mixture of air and gas flows inwardly through the passages 12 over the surface of the radiants 16 heating them to incandescence, which adds much to the heat within the housing, enabling a saving in the 100 amount of gas consumed.

I desire it to be understood that the specific constructions herein described may be varied without departing from the spirit and scope of the invention as defined in the 105 appended claims.

Having thus described the invention what I claim and desire to protect by Letters Patent is:

1. A gas range comprising an oven having a supported burner located therein, a radiant above and supported to be removable independent of the said burner, the radiant having a baffle plate immediately thereabove and of considerably less horizontal area than the horizontal area of the oven, for the purpose described.

2. A gas range having an oven, a burner supported within the oven, a radiant removably supported above the burner, said radiant carrying a baffle plate immediately thereabove, the radiant and baffle plate being bodily removable from the said burner, for the purpose described.

3. A gas range comprising an oven having a burner supported therein, of a radiant frame removably supported upon the said burner, a radiant attached to the said frame, and a baffle plate immediately above the radiant, said baffle plate attached to the ra-

diant frame, whereby the radiant and baffle are removable together from the said burner.

4. A gas range comprising a housing, parallel blue flame burners supported within the housing between its ends, radiant supports radiants supported thereby, a baffle plate immediately above and attached to the radiants, the baffle plate being considerably smaller in area than the interior area 10 of the housing.

5. A burner for a gas range comprising parallel blue flame burners, a baffle plate there above, radiant supports attached to the baffle plate, radiants within the said 15 supports, said supports adapted to rest upon the said burners, for the purpose described.

6. A gas burner for gas ranges comprising parallel blue flame burners supported within the gas range, a baffle plate above the 20 said burners having downwardly extending supporting arms at its edges, radiant supports connected with the said baffle and removed therefrom to afford a space for air

and heat, and a radiant support at its center, whereby the device is adapted to operate 25 as described.

7. A radiant construction for parallel blue flame burners of a gas range comprising a horizontal baffle plate carrying at its opposite edges and at its center radiant rail supports, horizontal radiants having their opposite edges supported in the said rails, the said device adapted to rest upon the said blue flame burners.

8. A radiant construction for blue flame 35 burners of gas ranges comprising a baffle plate, radiant supporting rails attached to but removed from opposite edges of the baffle, radiant supporting rails attached to its center, and radiants with their opposite 40 edges supported in their rails, the said device adapted to be superimposed upon blue flame burners, for the purpose described.

In testimony whereof I hereunto affix my signature.

ARTHUR STOCKSTROM.
